UNITED STATES PATENT OFFICE

ERNST VÖLCKER, OF BERNBURG, GERMANY

METHOD OF HEATING BOILER PLANTS

Application filed January 19, 1925, Serial No. 3,422, and in Germany January 28, 1924.

This invention relates to water tube boilers of the type comprising a lower drum, an intermediate drum and an upper drum, said intermediate drum being connected by nests of water tubes to the upper and lower drums.

The invention consists in a steam boiler of the type referred to and comprising return tubes outside of the boiler casing and connected to the upper and lower drums, so as to provide a return path which is not heated by the fire for the water which flows out of the upper drum, and guiding means within the boiler casing for guiding the heating gases so as to flow first across the tubes connecting the upper and intermediate drums, then through and between the tubes connecting the lower and intermediate drums. These features are each known per se but they have never been used at the same time in one and 20 the same boiler plant, if they are used all together they ensure however a circulation of water and steam free of disturbance through the entire boiler system.

Four embodiments of the invention are shown, by way of example, on the Figures 1 to 4 of the accompanying drawings.

Figure 1 shows diagrammatically in front elevation a boiler system of the simplest type according to the invention.

Figure 2 is a similar view showing a modified form of construction of the improved boiler system.

Figure 3 is a similar view showing two combined boiler systems, and

Figure 4 is a similar view to Figure 3 showing modifications of the two combined boiler systems.

The boiler system shown in Fig. 1 consists of a lower drum 12, an intermediate drum 13, an upper drum 14, a feeding drum 15 and a steam drum 16 situated above the feeding drum. The lower drum 12 and the intermediate drum 13 are connected the one with the other by smaller diameter tubes 17. Tubes 18 of greater diameter than tubes 17 connect the intermediate drum 13 with the upper drum 14. Down pipes 19 of rather great diameter connect the upper drum with the feeding drum 15 and ascent tubes 20 of great diameter connect the upper drum 14

with the steam drum 16, this steam drum being connected with the feeding drum 15 by vertical tubes 21 of great diameter. Two large pipes 22, situated outside the heating chamber connect the feeding drum 15 with the lower drum 12.

The heating gases flow directly with the arrows b vertically upward and then between the intermediate drum 13 and the upper drum 14 down again in order to flow along a serpentine path and in counter-current around the tubes of the lower nest of tubes 17 to escape through the economizer to the chimney.

The boiler system shown in Fig. 2 consists of a lower drum 24, a lower intermediate drum 25, an upper intermediate drum 26 and an upper drum 27, these drums being situated the one above the other and connected the one with the other by tubes 28, 29, 30. Outside the heating chamber laterally of and slightly below the upper drum 27 a feeding drum 31 is arranged which is connected with said upper drum 27 by a lower tube 32 similar to a down pipe and by an upper tube 33 similar to an ascending pipe. The feeding drum 31 is further connected by down pipes 34, situated outside the heating chamber, with the lower drum 24 and by ascending pipes 35 with the steam drum 36. More than four drums might be arranged the one above the other. The flue gases flow in the direction of the arrow c on a serpentine path through between the connecting tubes 30, 29 and 28 between the vertically superposed drums 24, 25, 26, 27 so that they flow first around the nest of tubes 30, then around the intermediate nest of tubes 29 and finally around the lower nest of tubes 28. The mixture of steam and water rises from the lower drum 24 vertically up to the upper drum 27. From this upper drum 27 the hot water or the mixture of steam and water flows through the down pipes 32 to the feeding drum 31, the steam being conducted from the upper drum 27 through the ascending pipes 33 into the feeding drum 31 from where it rises into the steam drum 36 from which it is withdrawn. The water is conducted through the down pipes 34 from the feeding drum 31 back to

the lower drum 24. The lower connecting tubes 28 are of smaller diameter and shorter than the intermediate tubes 29 which again are of smaller diameter and shorter than the upper tubes 30, the lower nest of tubes 28 comprising a greater number of tubes than the intermediate nest of tubes 29 which again comprises more tubes than the upper nest of tubes 30. The heating surface decreases therefore gradually from below upward, the temperature of the heating gases increasing from below upward, whereby the temperature of the heating gases is adapted to the heating surface at their disposal or inversely the heating surface is adapted to the temperature of the heating gases.

The boiler plant shown in Fig. 3 is composed of two juxtaposed boiler systems of the type shown in Fig. 2 having a common feeding drum 31^a and a common steam drum 36^a connected with one another by tubes 35^a. The flue gases flow first from above downward in serpentine shape in the direction of the arrow *d* through the nest of tubes 30^a, 29^a, 28^a of the left boiler system and are then conducted upward between the two boiler systems without coming in contact with the same to flow finally through the nests of tubes 30, 29, 28 of the right boiler system in serpentine shape from above downward in the direction of the arrow *e*. The flow of steam or water is in both boiler systems directed vertically upward from the lower drums 24, 24^a to the upper drums 27, 27^a and from these to the common feeding drum 31^a or steam drum 36^a while the water from the feeding drum 31^a flows back through the down pipes 34, 34^a to the lower drums 24, 24^a. The two boiler systems are parallel-connected while the heating gases flow successively through the casings of the two boiler systems.

The tubes of the boiler nests of the right hand boiler system are of less diameter but more numerous than those of the left hand boiler system in order to increase the heating surface of the right hand boiler system in accordance with the decreasing heating temperature. A further compensation of temperature between the left and right boiler systems is enabled by a register 37 adapted to cover more or less an aperture 38 in the partition 39 which separates the two boiler systems from one another so that not all the heating gases flow from the uppermost nest of tubes 30^a of the left boiler system to the second nest of tubes 29^a of the same boiler system but part of said heating gases flow directly to the uppermost nest of tubes 30 of the right hand boiler system.

The form of construction shown in Fig. 4 is designed for coal dust furnaces and composed of two boiler systems of the type shown in Fig. 1 which are arranged at the side of one another and have each a complete independent water or steam circulation. The two

boiler systems have one common furnace. The coal dust is burned in an intermediate heating chamber 40 and the heating gases flow from this heating chamber 40 at first in serpentine path in the direction of the arrow *f* through between the tubes of the upper nest of tubes 18 or 18^a and then through between the tubes of the lower nests of tubes 17 or 17^a. Each boiler system may evidently comprise more than three superposed drums.

All the boiler plants above-described have in common the characteristic features that at least three drums are arranged vertically above one another or on an inclined line the one above the other and connected with one another by means of nests of boiler tubes; that the drums are insulated from the heating chamber, that the heating gases flow through between the tubes of the nest of tubes from above downward and that the down pipes connecting the upper drum and the lower drum are situated outside the heating chamber. The arrangement according to which the drums are arranged vertically the one above the other and connected with one another by nests of straight tubes are especially practical as the ascent of the steam and water mixture takes place in vertical direction so that it encounters no resistance in inclined tubes.

By the insertion of one or more drums between the upper and lower drums the connecting tubes between these two drums become shorter wherefrom results an essential improvement of the technical effect as short tubes work much more freely as regards load on the cross sectional area than long tubes do. The intermediate drums serve as equalization space and fulfill a special purpose in the whole boiler system as they contain a great reserve of highly valuable prepared water so that they ensure the most rapid generation of steam in upward direction.

The loading temperature, the number of tubes, the length of tubes and the cross section of tubes are mutually regulated in order to produce a gradually increasing speed of the steam and water mixture from the lower drum up to the upper drum. The construction of the several nests of tubes is subordinated to this purpose and it might be in case of requirement different from the constructions and arrangements which have been described above and are shown in the accompanying drawing.

I claim:—

1. A boiler comprising in combination a boiler casing, a lower drum and an intermediate drum arranged the one vertically above the other in said casing, an upper drum vertically above said intermediate drum, a lower nest of tubes within said casing and connected to said lower drum and intermediate drum, an upper nest of tubes within said casing and connected to said intermediate

drum and upper drum, an inlet in the boiler casing for admitting heating gases to said boiler casing and means arranged within the casing for guiding the heating gases so as to flow first through and between the tubes of the upper nest of tubes and then through and between the tubes of the lower nest of tubes, and means connected to said upper drum and lower drum and comprising pipes shielded from the heating gases for establishing open communication between said upper drum and lower drum, for the purposes set forth.

2. A boiler comprising in combination a boiler casing, a lower drum and an intermediate drum arranged the one vertically above the other in said casing, an upper drum vertically above said intermediate drum, a lower nest of tubes within said casing and connected to said lower drum and intermediate drum, an upper nest of tubes within said casing and connected to said intermediate drum and upper drum, said second nest of tubes comprising a smaller number of tubes of greater diameter than the tubes of the first mentioned nest of tubes, an inlet in the boiler casing for admitting heating gases to said boiler casing and means arranged within the casing for guiding the heating gases so as to flow first through and between the tubes of the upper nest of tubes and then through and between the tubes of the lower nest of tubes, and means connected to said upper drum and lower drum and comprising pipes shielded from the heating gases for establishing open communication between said upper drum and lower drum, for the purposes set forth.

3. A boiler comprising in combination a boiler casing, a lower drum and an intermediate drum, arranged the one vertically above the other in said casing, an upper drum vertically above said intermediate drum, a lower nest of tubes within said casing and connected to said lower drum and intermediate drum, an upper nest of tubes within said casing and connected to said intermediate drum and upper drum, an inlet in the boiler casing for admitting heating gases to said boiler casing and means arranged within the casing for guiding the heating gases so as to flow first through and between the tubes of the upper nest of tubes and then through and between the tubes of the lower nest of tubes, a feed drum arranged below said upper drum but above said intermediate drum, pipes connected to said feed drum and upper drum and shielded from said heating gases and pipes connected to said feed drum and lower drum and shielded from said heating gases, for the purposes set forth.

4. A boiler comprising in combination a boiler casing, a lower drum and an intermediate drum vertically above said lower drum in said casing, an upper drum above said intermediate drum, a lower nest of tubes connected to said lower drum and intermediate

drum, an upper nest of tubes connected to said intermediate drum and upper drum, a feed drum above said intermediate drum, means connected to said feed drum and upper drum for establishing open communication between said feed drum and upper drum, means connected to said feed drum and lower drum for establishing open communication between said feed drum and lower drum, a steam drum above said upper drum, means connected to said steam drum and upper drum for establishing open communication between said steam drum and upper drum, an inlet in said boiler casing for admitting heating gases thereto and means arranged within the casing for guiding the heating gases so as to flow first through and between the tubes of the upper nest of tubes and then through and between the tubes of the lower nest of tubes, as and for the purposes set forth.

5. A boiler as set forth in claim 4, having pipes connected to the steam drum and feed drum for establishing open communication between said drums.

6. A boiler comprising in combination a boiler casing, a lower drum and an intermediate drum vertically above said lower drum in said casing, an upper drum outside said casing and vertically above said intermediate drum, a lower nest of tubes connected to said lower drum and intermediate drum, an upper nest of tubes connected to said intermediate drum and upper drum, a feed drum arranged outside said casing and below the upper drum but above the intermediate drum, a steam drum vertically above said feed drum, down pipes of large diameter connected to the upper drum and feed drum, ascent pipes of large diameter connected to said upper drum and steam drum, vertical pipes of large diameter connected to said steam drum and feed drum, an inlet inside said boiler casing for admitting heating gases thereto, return pipes of large diameter connected to said feed drum and lower drum, said pipes being shielded from the said heating gases and means arranged within the boiler casing for guiding the heating gases so as to flow first through and between the tubes of the upper nest of tubes and then through and between the tubes of the lower nest of tubes, as and for the purposes set forth.

7. A boiler comprising in combination a heating chamber, means for supplying pulverized fuel to said heating chamber, a boiler casing on each side of said heating chamber, a lower drum and an intermediate drum in each of said boiler casings, an upper drum above each of said intermediate drums, said lower, upper and intermediate drums being arranged vertically the one above the other, lower and upper nests of vertical tubes connected to said lower and intermediate drums and said intermediate and upper drums re-

spectively, an inlet in each boiler casing opposite the upper nest of tubes for admitting heating gases from said heating chamber to the upper nest of tubes, baffles within said boiler casings for guiding the heating gases between the lower nests of tubes and means connected to said upper drums and lower drums and comprising pipes shielded from the heating gases for establishing open communication between the upper and lower drums.
